United States Patent Office

Des. 224,340
Patented July 18, 1972

224,340

DISC DISPENSER

Walter Swirple, 8444 Lochdale,
Dearborn Heights, Mich. 48127

Filed Apr. 21, 1971, Ser. No. 136,284

Term of patent 14 years

Int. Cl. D9—99

U.S. Cl. D52—2

Fig. 1

Fig. 2

Fig. 3

Fig. 4

Fig. 5

FIG. 1 is a top plan view of a disc dispenser showing my new design;

FIG. 2 is a left side elevational view of FIG. 1;

FIG. 3 is a front side elevational view of FIG. 1, the rear side being a mirror image thereof;

FIG. 4 is a right side elevational view of FIG. 1; and

FIG. 5 is a bottom plan view of FIG. 1.

I claim:

The ornamental design for a disc dispenser, substantially as shown and described.
